224,652

CHAIR

Harry Zellick, 86 Hyde Ave. 02158, and Louis H. Zellick, 106 Withington Road 02160, both of Newton, Mass., and Phillip Zellick, Boston, Mass. (47 Nottinghill Road, Brighton, Mass. 02135)

Filed Mar. 4, 1971, Ser. No. 121,226

Term of patent 7 years

Int. Cl. D6—02

U.S. Cl. D15—1

FIG. 1 is a front perspective view of a chair, showing our design;

FIG. 2 is a right side elevational view of the chair, the left side being a mirror image thereof;

FIG. 3 is a front elevational view of the chair;

FIG. 4 is a rear elevational view of the chair;

FIG. 5 is a top plan view of the chair.

We claim:

The ornamental design for a chair, as shown and described.

References Cited

UNITED STATES PATENTS

D. 181,731	12/1957	Jones et al.	-----	D15—1
D. 190,645	6/1961	Sundberg et al.	-----	D15—1
D. 219,583	12/1970	Zellick et al.	-----	D15—1

BRUCE W. DUNKINS, Primary Examiner